UNITED STATES PATENT OFFICE

CHARLES F. DRECKSCHMIDT, OF ST. LOUIS, MISSOURI

TABLE

Application filed March 31, 1930. Serial No. 440,229.

This invention relates to extension tables. One of the objects of the invention is to provide a table having a supplemental top section which may be readily placed in and removed from a position to form a part of the top table surface, and in a position in which it will be concealed when not in use, which will be simple in construction and economical to manufacture.

Another object of the invention is to provide means for moving such a supplemental top section, operable by the spread of the permanent sections into cooperating position, and manually operated means for dropping the supplemental section to concealed position.

Other and further objects will be apparent from the following detailed description.

The structure includes generally, a rigid frame including the legs, a pair of complementary sections, a supplemental movable middle section, means for maintaining the alignment of the complementary top sections, and means for raising and lowering the supplemental middle section. The construction and operation of the device will be understood from the following detailed description taken in connection with the accompanying drawings, in which

Fig. 1 is a side elevation of the table in contracted position.

Fig. 2 is a side elevation of the table in extended condition.

Fig. 3 is a central longitudinal vertical section of Fig. 1.

Fig. 4 is a vertical cross-section on line 4—4 of Fig. 8, showing the position of the table as it is also in Fig. 2.

Fig. 5 is a central cross-section of Figs. 1 and 3.

Fig. 6 is a top plan view partly in section showing the table in full extended position such as to operate the means to elevate the supplemental section.

Fig. 7 is a vertical section on line 7—7 of Fig. 6.

Fig. 8 is a top plan view partly in section of the table in extended position of which Fig. 2 is a side elevation.

Fig. 9 is a vertical section on line 9—9 of

Fig. 8, and, therefore, a central longitudinal vertical section of Fig. 2.

Fig. 10 is a top plan view partly in section of the table in extended position similar to Fig. 8, but with the operating means moved to such a position as to permit the central section to drop to concealed position.

Fig. 11 is a vertical section on line 11—11 of Fig. 10.

A frame includes the end rails 1, the side rails 2, the legs 3, and the guide rails 4, all rigidly secured together. The guide rails 4 have on each of their sides a dove-tailed groove 5 to receive a tongue 6 on cooperating rails secured to the top sections. A base plate 7 is rigidly secured to the bottom side of the guide rails 4 and serves to give greater rigidity to the frame, to provide a support for the supplemental section, and to provide a support for guides to maintain the complementary top sections in proper alignment with each other and with the frame.

The permanent complementary top sections each includes a top member 8 forming the table top when the table is in contracted position, and with the supplemental metal section forming the table top when the table is in extended position. End aprons 9 and side aprons 10 are secured to and depend from the top members 8. Corner cleats 11 may be provided to give greater rigidity to the top structure. The top members 8 are provided at their adjacent edges with dowel pins 12 and sockets 13. Rails 14 are secured to one of the top members 8, and rails 15 are secured to the other top member 8, and each has a tongue 6 cooperating in the groove 5 in the guide rails 4. It is thus seen that the complementary top members are movable to and from each other and movable with respect to the frame.

Means are provided to co-ordinate the movements of the two complementary top sections so that when one section is moved in one direction with reference to the frame, the other section will be moved to the same extent in the opposite direction. These means include a rack 16 mounted on top of each of the rails 14 and 15, and meshing with a pinion 17 pivotally secured to the rail 4.

Blocks 18 are rigidly secured to the base 7.

and respectively bear against the outer sides of the outer rails 14 and 15. Blocks 19 are also rigidly secured to the base 7 and respectively bear against the inner sides of the inner rails 14 and 15. The blocks 18 and 19 thus serve the purpose of retaining engagement of the rails 14 and 15 with the rails 4. The blocks 19 are formed so as to have functions in connection with the middle supplemental section, which will be apparent from the later portions of this description.

The middle supplemental section which, as already noted, is provided to be used as a part of the table top when desired, includes a top member 20 having sockets 21 to receive the dowel pins 12, and dowel pins 22 to engage in the sockets 13.

Guide pins 23 are rigidly secured to the top member 20 and engage in bores 24 in the blocks 19 so that the top member 20 is maintained in horizontal position at all times, and may thus, with respect to the frame, be moved only in a vertical position. When the supplemental top member 20 is dropped to its lowermost position its bottom surface rests upon and is supported by the tops of the blocks 19. It will thus be seen that when the supplemental member 20 is dropped to its lowermost position the permanent top sections may be moved toward each other over it and thereby cover and conceal the supplemental section. If the complementary top sections be spread apart, and the member 20 raised to an alignment with the complementary sections and supported in that position, the complementary sections may be closed against the supplemental section and thus form a table top of extended dimensions.

Means are provided for raising and supporting the supplemental section in alignment with the complementary sections, and thereby provide an extended table top surface. A member 25 is positioned between the base element 7 and the supplemental element 20. This intermediate element 25 has at each side a pin 26 sliding in a groove 27 in the side of the block 19. These grooves 27 are inclined for a part of their distance, and are horizontal for a part of their distance. Wedge-shaped blocks 28 are secured to the underside of the intermediate element 25 and are positioned so that their inclined surfaces will engage with the side edge of the base 7. The arrangement of the pins 26 in cooperation with the groove 27, and the arrangement of the wedge blocks 28 in cooperation with the base 7, is such that when the intermediate element 25 is moved forward it will be elevated. Lugs 29 in the form of metal domes are placed on the upper surface of the intermediate element 25 and are adapted to cooperate with cleats 30 secured to the underside of the supplemental member 20. Thus when the intermediate element 25 is moved forward it is raised and the lugs

29 contact with the cleats 30 elevating the member 20 to a position level with the permanent top sections 8.

Means are provided for moving the intermediate element 25 forward, which consist of a flexible element 31 secured at one end to a cleat 32 attached on the bottom side of the intermediate element 25, and secured at its other end to the cleat 11 secured to the bottom side of one of the permanent top elements 8. Thus when the permanent complementary top elements are fully extended the intermediate element 25 is brought forward and raises by wedging action the supplemental top element 20 to an aligned position. By moving the complementary top members together the supplemental member is secured between them.

Means are provided for releasing the supplemental member which comprise a flexible element 34 secured to an end of the cleat 32 opposite the end to which the flexible element 31 is attached. The other end of the flexible element 34 is secured to one end of a lever 35 pivoted to a block 36 secured to one of the side frame members 2. The lever 35 is provided with a handle 37 for manual operation.

While the operation of the device may be understood from the preceding detailed explanation of its construction, a further description of this operation will assist in the understanding of the device. Figs. 1, 3 and 5 illustrate the table in its contracted position in which the supplemental section is concealed. Assuming it is desired to extend the table, the operator grasps one of the complementary end sections and pulls it away from the center; the guide rails 14 and 15 slide with respect to the rail 4, both complementary sections moving at the same rate by reason of the pinions 17 in mesh with the racks 16 attached to the guide rails 14 and 15. The complementary sections are spread until they assume the position shown in Figs. 6 and 7. By that movement the flexible member 31 pulls the intermediate member 25 to one side and in that movement, by reason of the engagement of the pins 26 in the inclined portion of the groove 27 and the engagement of the wedge member 28 with the base plate 7, the intermediate member 25 is raised, causing the lugs 29 to engage the cleats 30. The supplemental top section 20 is thereby raised to a position in which it is in alignment with the complementary top portions 8. The intermediate member 25 has been moved to such a position that the pins 26 rest in the horizontal portion of the grooves 27 and the wedge members 28 rest on top of the base plate 7. Thus the supplemental top 20 is positively supported in its uppermost position. The complementary sections may then be pushed together and closed upon the sup-

plemental section, and the device assumes the position illustrated in Figs. 2, 4, 8 and 9.

When the table is to be contracted, the lever 35 is moved by the handle 37 and, by reason of the flexible connection 34, the intermediate member 25 is withdrawn to such a position as to permit the supplemental element 20 to drop to its concealed position. The table after the withdrawal of the supplemental member 25, but before the supplemental section is dropped, is illustrated in Figs. 10 and 11. In actual practice, however, before the lever 35 is moved the complementary sections will be spread slightly so as to disengage the dowel pins 12 from the sockets 21 and the dowel pins 22 from the sockets 13.

A particular advantage rests in the method of support and the manual method of withdrawing the supporting elements in that the table will not be collapsed by reason of the accidental spreading of the complementary members. The supplemental section 20 will not drop until the intermediate member 25 has been withdrawn by manipulation of the lever 35.

The invention, therefore, accomplishes its purpose. A self-contained structure has been provided which includes a supplemental top section which may be readily placed in and removed from its useful position, and which is simple in construction and economical to manufacture. There has also been provided means for moving and positively supporting the supplemental section operable by the spread of the complementary permanent sections. The construction is such also as to prevent accidental displacement of a supplemental section, since its movement into inoperative or concealed position is entirely dependent upon manual operable means.

It is obvious that various changes may be made in the details of construction without departing from the spirit of this invention, and that within the scope of the appended claims the invention is not limited to the specific means illustrated and described.

I claim:

1. In an extension table, end sections movable toward and away from each other, a vertically movable center section, a rigid base below said center section, blocks rigid on said base having therein grooves that are horizontal for a part of their length and inclined for a part of their length, a movable element located between said blocks, projections from the ends of said movable element engaging in said grooves, means for operating said movable element to raise said center section to position in alinement with said end sections, and means in connection with said center section engaging said blocks and holding said center section from lateral movement in either direction.

2. In an extension table, end sections mov-

able toward and away from each other, a vertically movable center section, a movable element supported for sliding movements below and relative to said center section, means for moving said element, means for holding said element in a horizontal position when it is moved, means for moving said center section by said element to position between said end sections, and means other than said end sections preventing said center section from tilting and from moving laterally when said center section is moved as aforesaid.

3. In an extension table, end sections movable toward and away from each other, a vertically movable center section, supports for supporting said center section below said end sections when said end sections are adjacently disposed, a movable element, means for moving said element below and with respect to said center section and for moving said center section vertically by said movable element, and devices other than said end sections holding said center section from moving laterally and from inclining.

4. In an extension table, end sections movable toward and away from each other, a vertically movable center section, supports for supporting said center section below said end sections when said end sections are adjacently disposed, a movable element, means for moving said element below and with respect to said center section and for moving said center section vertically by said movable element, devices other than said end sections holding said center section from moving laterally and from inclining, a connection for moving said element in one direction by one of said end sections, and a lever for moving said element in the other direction to lower said center section.

5. In an extension table, end sections movable toward and away from each other, a vertically movable center section, a rigid base below said center section, blocks rigid on said base having therein grooves that are horizontal for a part of their length and that are inclined for a part of their length, a movable element located between said blocks, projections from the ends of said movable element engaging in said groove, parts in connection with said movable element engaging said base and cooperating with said projections and said grooves to raise said movable element when said element is moved laterally in one direction, means for moving said movable element laterally in said direction, guide connections between said center section and said blocks holding said center section from lateral movement, and means for raising said center section by said movable element.

6. In an extension table, end sections movable toward and away from each other, a vertically movable center section, supports for supporting said center section below said end sections when said end sections are jux-

taposed, a movable element for raising said center section from said supports to position between and in alinement with said end sections, means for moving said movable element under and with respect to said center section, means for elevating said movable element when said element is moved as aforesaid and thereby moving said center section vertically to position between and in alinement with said end sections, and means in connection with said center section engaging said supports and holding said center section in a horizontal position.

7. In an extension table, end sections movable toward and away from each other, a vertically movable center section, supports for supporting said center section below said end sections when said end sections are juxtaposed, a movable element for raising said center section from said supports to position between and in alinement with said end sections, means for moving said movable element under and with respect to said center section, means for elevating said movable element when said element is moved as aforesaid and thereby moving said center section vertically to position between and in alinement with said end sections, means in connection with said center section engaging said supports and holding said center section in a horizontal position, and devices for moving said movable element in the opposite direction to permit said center section to move downwardly onto said supports.

35 CHARLES F. DRECKSCHMIDT.
